UNITED STATES PATENT OFFICE.

HENRY S. PECK, OF NORTH EAST, PENNSYLVANIA, ASSIGNOR TO ROBERT J. MOORHEAD, OF SAME PLACE.

SUSPENDED ADJUSTABLE CHAIR.

SPECIFICATION forming part of Letters Patent No. 425,248, dated April 8, 1890.

Application filed August 9, 1889. Serial No. 320,214. (No model.)

To all whom it may concern:

Be it known that I, HENRY S. PECK, a citizen of the United States, residing at North East, in the county of Erie and State of Pennsylvania, have invented certain new and useful Improvements in Suspended Adjustable Chairs; and I do hereby declare the following to be a full, clear, and exact description of the invention, such as will enable others skilled in the art to which it appertains to make and use the same.

This invention relates to suspended adjustable chairs; and it consists in certain improvements in the construction of the same, as will be hereinafter fully set forth, and pointed out in the claim.

My invention is illustrated in the accompanying drawings as follows:

Figure 1 is a perspective view, and Fig. 2 is an elevation view, of part of the back, taken from the rear of the chair.

The chair is composed of the bottom A, back B, and foot-rest C, which parts are hinged or joined together at a^2 and a^3 . The back and bottom have arms or side pieces b' and a' , and the whole chair is made up of round work, excepting the flat pieces which form the back, seat, and foot-rest proper. The construction of these parts is similar to that shown in Letters Patent granted to me December 1, 1885, and numbered 331,434, and therefore need not be further explained, except in so far as it differs in construction from that shown in said patent.

The chair seat or bottom is suspended by two ropes D D on each side, which pass from a ring F down through the arm-pieces a' a' and through the side pieces a a near each end thereof. The back is sustained by ropes E E, which pass from the rings F through the side pieces b of the back at e. The ropes E are, in fact, one rope, or, rather, they may be, as shown, one rope, which passes from a ring F on one side, through the holes e, across the back, and up to the other ring. The adjustment of the back B to any angle is effected by taking up or letting out the loop of rope E back of the back of the chair at H. At the point H a rope-clamp may be used, or any convenient method of fastening.

The rope-clamp I show is to be the subject of another application for a patent, being Serial No. 320,213, filed August 9, 1889, and need not be explained here, particularly so as any convenient fastening can be used.

The foot-rest C is pivoted to the bottom B on the rung a^3 inside the side pieces a , and its outer end is sustained by hooks c' , which engage with staples c^2 on the arm-pieces a' . When the foot-rest is not wanted in an extended position, it folds back under the seat, as shown by dotted lines in Fig. 1, and is secured there by engaging the hooks c with the staples c^3 .

When the chair is made for use as a child's chair, I thread on the forward cords D the bar G, which serves to hold the child in place in the chair. When not wanted in front of the child, the bar G can be slid up the cords to the rings F out of the way.

In Letters Patent No. 285,665, of September 25, 1883, and No. 296,775, of April 15, 1884, to myself, and No. 305,003, of September 9, 1884, to Howell, and No. 402,110, of April 23, 1889, to Schutt, there are shown constructions having many of the general features I here show; but I do not now claim any of the features there shown, my present invention consisting in peculiarities of construction not found in the constructions cited above.

What I claim as new is—

In a suspended adjustable chair, the combination of a seat, means for suspending said seat, a back pivoted at its lower end to said seat, cords for supporting the upper end of said back, which extend from the suspending means above the seat through openings at the sides of the back near its top, and a cord-fastening appliance at the rear of said back, by which said cords can be taken up or let out, as desired, and thereby regulate the angle of inclination of said back.

In testimony whereof I affix my signature in presence of two witnesses.

HENRY S. PECK.

Witnesses:

JNO. R. HALLOCK,
WM. P. HAYES.
